(57) **CLAIM**

The ornamental design for solar animal repeller, as shown and described.

DESCRIPTION

FIG. 1 is a front perspective view of solar animal repeller, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is an enlarged detail view of area 9 in FIG. 1; and, FIG. 10 is an enlarged detail view of area 10 in FIG. 1.

The dash-dash broken lines in the drawings depict portions of the solar animal repeller that form no part of the claimed design.

The dash-dot-dash broken lines in FIGS. 1, 9 and 10 show the extent of the enlargements shown in FIGS. 9 and 10, and form no part of the claimed design.
